Primary Examiner—Austin Murphy*(74) Attorney, Agent, or Firm*—Stuart M. Goldstein(57) **CLAIM**

The ornamental design for a multi-purpose firefighting tool, as shown and described.

DESCRIPTION

FIG. 1 is an isometric view of the multi-purpose firefighting tool of the present invention.

FIG. 2 is the front view of the multi-purpose firefighting tool of the present invention.

FIG. 3 is the rear view of the multi-purpose firefighting tool of the present invention.

FIG. 4 is an elevation view of the multi-purpose firefighting tool of the present invention.

FIG. 5 is an elevation view showing the other side of the multi-purpose firefighting tool of the present invention.

FIG. 6 is the bottom view of the multi-purpose firefighting tool of the present invention; and,

FIG. 7 is the top view of the multi-purpose firefighting tool of the present invention.

1 Claim, 4 Drawing Sheets**FIG. 1**

FIG. 2

FIG. 3

FIG. 4

FIG. 5

FIG. 6

FIG. 7
